(57) **CLAIM**

The ornamental design for an indirect lighting arrangement for a vehicle, as shown and described.

DESCRIPTION

FIG. 1 is a perspective view of an indirect lighting arrangement for a vehicle showing our new design;

FIG. 2 is a bottom view thereof;

FIG. 3 is a top view thereof;

FIG. 4 is a side view looking in a port direction;

FIG. 5 is a side view looking in a starboard direction;

FIG. 6 is a side view looking in an aft direction;

FIG. 7 is a side view looking in a forward direction; and, FIG. 8 is a sectional view of the indirect lighting arrangement depicted in FIG. 2 along line 8-8.

The broken lines illustrate structure and environment that form no part of the claimed design.
